UNITED STATES PATENT OFFICE.

HENRY W. HIRSCHFELD, OF MERIDEN, CONNECTICUT, ASSIGNOR TO THE
MERIDEN BRITANNIA COMPANY, OF SAME PLACE.

DESIGN FOR A SPOON OR FORK HANDLE.

SPECIFICATION forming part of Design No. 16,568, dated March 16, 1886.

Application filed December 26, 1885. Serial No. 186,800. Term of patent 14 years.

To all whom it may concern:

Be it known that I, HENRY W. HIRSCHFELD, of Meriden, in the county of New Haven and State of Connecticut, have invented a new 5 Design for Spoon and Fork Handles; and I do hereby declare the following, when taken in connection with accompanying drawings, and the letters of reference marked thereon, to be a full, clear, and exact description of the 10 same, and which said drawings constitute part of this specification, and represent, in—

Figure 1, a face view; Fig. 2, a vertical central section.

This invention relates to a design for the 15 ornamentation of the face of the handle of spoons, forks, and like articles; and it consists in a series of diagonal parallel grooves across the face of the handle, forming a corresponding series of diagonal ribs, as shown. The 20 outline of the handle is of the usual form.

The ornamentation on its face consists of a series of parallel grooves running diagonally from side to side, forming the representation of a like series of diagonal ribs over the face of the handle, as shown in the accompanying 25 illustration.

I claim—

The design for the ornamentation of spoon and fork handles, consisting in a series of parallel grooves running diagonally across the 30 face of the handle from side to side, and forming the representation of a series of parallel ribs, the said series of parallel ribs extending from the tip of the handle downward, as shown in the accompanying illustration.

HENRY W. HIRSCHFELD.
